UNITED STATES PATENT OFFICE.

VICTOR J. SHEPARD, OF LIMA, OHIO, ASSIGNOR TO LIMA LOCOMOTIVE CORPORATION,
OF LIMA, OHIO, A CORPORATION OF OHIO.

RADIAL TRAILER-TRUCK.

1,105,162.

Specification of Letters Patent.

Patented July 28, 1914.

Application filed May 5, 1914. Serial No. 836,388.

To all whom it may concern:

Be it known that I, VICTOR J. SHEPARD, a citizen of the United States, residing at 119 South Baxter street, Lima, county of Allen, and State of Ohio, have invented certain new and useful Improvements in Radial Trailer-Trucks, fully described and represented in the following specification and the accompanying drawings, forming a part of the same.

This invention relates to locomotive engines having auxiliary frame-bars extended backwardly from the main-frames to support the load at the rear end. In such case, a radial truck is fitted to support the weight upon such auxiliary frame-bars, and means is required for transmitting the load upon such frame through suitable springs to the journal-boxes of the radial truck-wheels.

As a radial truck is pivoted to the frame of the locomotive, it is compelled, when moving around curves, to swing to one side or the other of the frame, and as the springs and their equalizers have a fixed relation to the frame, it is necessary to provide some connection between the bearing-boxes of the radial truck-axle and such springs, which will permit movement of the bearings to different positions under the frame, and at the same time transmit to the springs any vertical motion of the bearings. This is effected in the present construction through spring-bearing-blocks movable vertically in sockets which are held rigidly by the side-frames, over the journal-bearings of the truck-axle, the foot of each bearing-block being fitted to rest upon the top of one of the journal-bearings, so that the bearing may slide beneath such foot in moving to various positions, while its vertical movements are transmitted to the spring through such bearing-block.

The top of the journal-bearing-box is preferably provided with a flat load-plate, and the bottom of the bearing-block with a self-adjusting bearing-plate, which rests upon such load-plate, and maintains its bearing thereon when the journal-bearing is tipped out of its normal position.

The spring is preferably supported within the bearing-block by a guide-block having a rocking connection therewith to compensate for the various positions of the spring as the bearing-block is moved up or down in its socket.

The construction will be understood by reference to the annexed drawing, which illustrates one form of the invention, and in which—

Figure 1 is a side elevation of the radial truck and the frame-bars connected therewith; Fig. 2 is an elevation, partly in section, where hatched, of the bearing-block and its attachments, the spring being indicated by dotted lines; Fig. 3 is a plan of the parts shown in Fig. 1; Fig. 4 is a plan of the bridge-bar which contains the socket for the bearing-block; Fig. 5 is a plan of the radial truck detached from the other parts; Fig. 6 is a plan of the bridge-bar with the bearing-block and its attachments, the ends of the bridge being broken for want of room on the drawing; Fig. 7 is a perspective view of the bearing-block, the nearer half of the same being removed to show its interior construction; Fig. 8 is a perspective view of the guide-block which has a rocking connection with the bearing-block; and Fig. 9 is a perspective view of the bearing-plate with spherical boss upon the top to fit a concave recess in the bottom of the bearing-block.

The locomotive-frames A are shown connected by a cross-beam A' and have auxiliary frame-bars B bolted thereto and extended backwardly beneath the boiler fire-box C, and connected at their rear ends by foot-plate D.

The rear driving-axle E is shown with driving-wheels F, and the radial truck-frame G is provided with bearings H for the axle I of the truck-wheels J.

The truck-frame G is formed with a hinge-lug a at its forward end fitted to a pivot a' carried by the cross-tie A', and the rear end of the truck-frame is provided with a lug K fitted between centering springs L in the usual manner, such springs being mounted movably upon the frame B or foot-plate D.

The truck-wheels J operate outside of the auxiliary frame-bars B, and the truck-frame G supports the journal-bearings H outside of the wheels J.

To support a semi-elliptic spring H' over each bearing, and to make the desired connection between the springs and the journal-bearing, the bearings are furnished each, as shown in Fig. 1 on the top with a flat load-plate c, and brackets M are projected

outwardly from the beams B at opposite sides of the bearings H and carry a bridge-bar or beam N, in the middle of which is formed a socket c', as shown in Fig. 4 to 5 carry a vertically movable spring-bearing-block d, which, when the truck-frame G is in its central position, stands over the center of the load-plate c. The brackets M and bars N form a rigid yoke over the journal.

10 The bearing-block is formed with a foot lettered d in Figs. 2 and 7, and with side-walls d' fitted to the opposite sides of the socket c', as shown in Fig. 6.

The base f and the side-walls f' are provided at their edges with ribs f² which serve to embrace the band of the spring, as shown in Fig. 3. The base f has upon its under side a segmental cylindrical projection e which is fitted to a transverse recess e' of similar 20 shape in the upper side of the foot d, so that the guide-block has a rocking connection with the bearing-block.

Ribs d² are formed at the edges of the walls d' and serve to limit the rocking movement of the guide-block.

The under side of the foot d has a spherical recess h, and a bearing-plate i is formed to rest upon the top of the journal bearing, and is provided with a spherical boss j fitted to the recess h.

At opposite sides of the sockets c' the bridge-bar is provided with openings or recesses O, which receive the lower corners of the spring H' and serve to hold the same in 35 its working position.

The bridge-bars are shown with slots O through which the links p' are extended to connect the ends of the spring H' with the bridge-bar and with an equalizing-bar Q. 40 This equalizing-bar is connected in the usual manner by link k with the semi-elliptic spring H² over the driving-axle E. The relation of the spring to the bearing-plate i is clearly shown in Fig. 2, where it will be 45 seen that the bearing-block can tip in any direction upon the bearing-plate i which rests upon the top of the journal-bearing, as shown in Fig. 1.

The rocking connection of the spring-guide-block f with the foot d of the bearing-block, is also clearly shown, as well as the clearance between the walls f' of the guide-block and the ribs d² upon the bearing-block which limit the rocking movement.

50 The load-plate c is provided upon the top of the journal-bearing H to furnish an area of width greater than the bearing-plate i, as shown in Fig. 5, so that the bearing-plate may retain its contact with the top of 55 the bearing when the radial truck assumes various lateral positions beneath the auxiliary frame-bars B.

Any vertical motion of the journal-bearing is thus transmitted to the spring by the 60 vertically movable bearing-block d while

the adjustability of the bearing-plate compensates for any deviation of the journal-bearings from their normal position.

It will be seen by reference to Fig. 3, that the auxiliary frames B, combined with the brackets M and bridge-bars N, form an exceedingly rigid construction, and furnishes a most efficient support for the spring-bearing-blocks which transmit the vertical movements of the journal-bearings to the 75

The construction of the parts connected with the spring-bearing-blocks is exceedingly cheap and simple and requires finish only where the bearing-plate rests upon the 80 load-plate of the bearing, and where the boss j is fitted to the recess h.

The parts above the journal-bearing may be used in common for engines of different classes, in cases where the truck below requires alteration, thus reducing the number of repair parts which it is necessary to carry 85 in stock for maintaining such trucks.

Having thus set forth the nature of the invention what is claimed herein is:

1. In a locomotive engine, the combination, with main-frames, and auxiliary frame-bars extended backwardly from such main-frames, of a radial truck-frame pivoted by suitable joint to the main-frame and having 90 journal-bearings for a single axle and truck-wheels, vertical sockets supported by the auxiliary frame-bars rigidly above the journal-bearings with a spring-bearing-block movable in each of such sockets and a 95 spring supported by such bearing-block, and the foot of each bearing-block being fitted to rest upon the top of one of the journal bearings, whereby the radial truck may move to various positions beneath the 100 springs, and the vertical movement of the journal-bearings be transmitted to the 105 springs in all the said positions.

2. In a locomotive engine, the combination, with main-frames having rear driving-wheels journaled in bearings therein, of auxiliary frame-bars extended backwardly from such main-frames, a radial truck-frame pivoted by suitable joint to the main-frame and having 110 bearings for a single axle and truck-wheels, each bearing having a horizontal load-plate upon the top, vertical sockets supported by the auxiliary frame-bars rigidly above such load-plates with a spring-bearing block movable vertically in each of such 115 sockets, and the foot of each bearing-block being fitted to rest upon one of said load-plates.

3. In a locomotive engine, the combination, with main-frames having driving-wheels journaled in bearings therein and auxiliary-frame-bars extended backwardly from such main-frames, of a cross-tie between the main-frames in the rear of the driving-axle, a radial truck-frame pivoted 125

to such cross-tie and having bearings for an axle outside of the wheels, each bearing carrying a flat load-plate upon the top, rigid yokes upon the outsides of the auxiliary frame-bars having each a vertical socket over such load-plate, a spring-bearing-block movable in each socket and having a concave recess upon its under side, and a bearing-plate fitted movably to the flat load-plate of

5 the journal and having a boss fitted to the concave recess.

10 4. In a locomotive engine, the combination, with main-frames, and auxiliary frame-bars extended backwardly from such main-frames, of a radial truck-frame pivoted by suitable joint to the main-frame and having journal-bearings for a single axle and truck-wheels, vertical sockets supported by the auxiliary frame-bars rigidly above the 15 journal-bearings, a spring-bearing-block movable vertically in each of such sockets, a spring-guide-block fitted within the spring-bearing-block and having a rocking connection therewith, and a spring fitted to the 20 guide-block to support the load on such bearing-block, the spring-bearing-block having a spherical recess upon its under side, and a bearing-plate fitted movably to the flat load-plate of the journal and having a 25 spherical boss engaged with the spherical recess, as and for the purpose set forth.

30 5. In a locomotive engine, the combination, with main-frames, and auxiliary frame-bars extended backwardly from such main-frames, of a radial truck-frame pivoted to the main-frame and having journal-bearings for a single axle and truck-wheels, each journal-bearing being provided upon the top with a flat load-plate, brackets projected 35 from the outer side of each of the auxiliary frame-bars with a bridge-bar connecting such brackets, a vertical socket in such

bridge-bar over the journal-bearing, a spring-bearing-block movable vertically in such sockets, a spring fitted to such bearing-block, and the lower end of the bearing-block fitted to rest upon the journal-bearing, whereby the bearings are movable laterally to various positions beneath such bearing-blocks and transmit their vertical movement 45 thereto in such positions.

50 6. In a locomotive engine, the combination, with main-frames, and auxiliary frame-bars extended backwardly from such main-frames, of a radial truck-frame pivoted to the main-frame and having journal-bearings for a single axle and truck-wheels, brackets projected from the outer side of each of the auxiliary frame-bars with a bridge-bar connecting such brackets and formed with a 55 vertical socket for a spring-bearing-block above the journal-bearing, and with clearance-spaces at each side of such socket for the lower part of an elliptic spring, a spring-bearing-block having foot with opposite 60 side-plates fitted to such vertical socket and such foot provided with a self-adjusting bearing-plate to rest upon the top of the journal-box, a guide-block fitted between the side-plates of the bearing-block and having 65 a rocking connection therewith and recessed to receive the band and body of the spring, ribs upon the plates of the bearing-block limiting such rocking movement, and a semi-elliptic spring having a center band fitted 70 to the recess of such guide-block and confined thereby to a mere rocking motion.

75 In testimony whereof I have hereunto set my hand in the presence of two subscribing witnesses.

VICTOR J. SHEPARD.
